(57) **CLAIM**

The ornamental design for a waist trainer, as shown and described.

DESCRIPTION

FIG. 1 is a front perspective view of a waist trainer showing our new design;

FIG. 2 is a front view thereof;

FIG. 3 is a back view thereof;

FIG. 4 is a left side view thereof;

FIG. 5 is a right side view thereof; and,

FIG. 6 is a top view thereof.

The thicker dash-dash broken lines shown in the drawings depict portions of the waist trainer that form no part of the claim design.

The thinner dash-dash broken lines shown in the drawings depict portions of the waist trainer that form no part of the claim design.

The dot-dash broken lines shown in the drawings depict boundaries of the claim that form no part of the claimed design.

1 Claim, 6 Drawing Sheets
